RUG.

No. 16,394.

Patented Nov. 24, 1885

UNITED STATES PATENT OFFICE.

RICHARD PAUL HEMMING, OF PHILADELPHIA, PENNSYLVANIA, ASSIGNOR
TO GEORGE W. ENNIS & CO., OF SAME PLACE.

DESIGN FOR A RUG.

SPECIFICATION forming part of Design No. 16,394, dated November 24, 1885.

Application filed October 26, 1885. Serial No. 181,003. Term of patent 3½ years.

To all whom it may concern:

Be it known that I, RICHARD PAUL HEMMING, a citizen of the United States, residing at Philadelphia, in the county of Philadelphia and State of Pennsylvania, have invented and produced a new and original Design for a Rug; and I do hereby declare that the photographic print accompanying this specification conveys to any one skilled in the art a clear understanding of the same, and is sufficient to enable such persons to use my invention.

The leading feature of my design consists in a center panel having a checker ground, upon which are represented Egyptian figures representing branches. At the ends of the panel are cross-strips of Egyptian ornamenta-

tion. The whole is surrounded by borders A B C, as shown in the photographic print.

The photographic print illustrates and represents one half of the design. The other half described, but not shown, is exactly like it.

What I claim as my invention is—

The design for a rug, consisting of a center panel having a checkered ground, upon which are represented Egyptian figures representing branches, with the ends of the panel ornamented by cross-strips, the whole surrounded by the borders A B C, as shown.

R. PAUL HEMMING.
